Inventor

Edward Walker

UNITED STATES PATENT OFFICE.

EDWARD WALKER, OF GRANTWOOD, NEW JERSEY.

FEEDER FOR CLOTHES WRINGERS.

Application filed June 23, 1924. Serial No. 721,829.

To all whom it may concern:

Be it known that I, EDWARD WALKER, citizen of the United States, residing at Grantwood, in the county of Bergen and State of New Jersey, have invented certain new and useful Improvements in Feeders for Clothes Wringer, of which the following is a specification.

My invention relates to an apparatus for 10 manually feeding clothing or other washable articles to a hand or power driven clothes wringer.

My invention has for its object to provide a readily manufactured feeder which will 15 furnish a hand rest for the operator and also prevent his fingers from being accidentally pulled in and mangled between the rollers of the wringer.

My invention has also for an object to 20 provide a feeding strip over which the ends of the washed articles will be spread out and folded so as to furnish a sufficiently broad contact surface for the rollers so as to prevent the tearing of the washed articles.

My invention has further for an object to 25 provide a feeder substantially shorter than the wringer rollers, said feeder being adapted to be readily applied to any part of the rollers so as to evenly distribute the washed

articles over the entire length of the rollers.

In the drawing:—

Figure 1 shows a swinging reversible feeder mounted on a clothes wringer.

Figure 2 shows the manner in which the 35 feeder is held and manipulated.

Figure 3 is an isometric view showing a detached type of feeder which is also adapted as a pick up for the washed articles.

Figure 4 shows the swinging reversible 40 feeder detached from the wringer.

Referring to the drawing in which like reference characters designate corresponding parts, 1 designates the wringer to which the feeder 2 is attached by means of hinges 3 which are at one end pivoted between the lugs 4 on the feeder and at the other end pivoted between brackets 5 which are mounted on the wringer posts 6 between which the rollers 7 operate compressing the wet clothes 14.

On each side of the wringer is a guide board 8 mounted in order to make it possible to reverse the operation of the wringer.

It is evident that the clothes in passing 55 through the wringer will be guided over the board 8 on the feed side of the wringer and

will, in leaving the wringer, be prevented from being wound around the lower roller by the guide board on the discharge side of the wringer. The guide boards 8 are the 60 usual flat strips conveniently supported on opposite sides of the rollers of an ordinary wringer.

The detached feeder 9, as well as the pivoted feeder 2, comprises a blunt edged feed 65 plate 10 having abutment strips 11 formed upon the ends thereof. These strips are arranged transversely of the plate 10 and extend equi-distances on opposite sides thereof. The forward edge of the plate 10 projects outwardly beyond the front edges of the strips 11, the latter edges being widened as indicated at 12 and designed to 70 engage the surfaces of the rollers 7. The length of each strip 11 on opposite sides of 75 the plate 10 is such that when adjacent ends of said strips are engaged with a guide board 8, as shown in Figure 2, the forward edge of the plate 10 will be substantially aligned with the space between the rollers 80 7 thus facilitating the guiding of the plate into said space. The forward edges of the abutment strips 11, by engaging the surfaces of the rollers 7, limit the inward movement of the plate between the rollers. 85

The mode of manipulation is as follows.

An end of the wet clothes 14 is picked up and folded over the blunt edged feed plate 10 and held in position by the thumb of the same hand that manipulates the feeder. 90

The handle 13 is located at the center of the feed plate 10 and is preferably made flat so that the thumb grip may be readily effected either on the feed plate proper or on the handle. 95

The feeder with the folded clothes end held as shown is now brought in front of the rollers so that adjacent ends of the abutment strips will rest on the guide board and at the same time press against the 100 rollers.

The projecting blunt edge of the feed plate is so proportioned that when the feeder is held as above described a sufficient contact friction between the rollers 105 and the clothes will arise so as to pull the clothes away from the feeder and through the wringer.

It is to be noticed that the guide board will in acting as a rest for the pivoted type of feeder 2 prevent any straining of the 110 hinges 3.

When using the detached type of feeder it ought preferably to be held in the hand when picking up the clothes, the projecting edge of the feed plate being readily inserted under the cloth when a thumb grip is easily secured, performing the entire feeding operation by means of one hand only.

I do not desire to be understood as limiting myself to the specific details of construction and arrangement as it is manifest that variations and modifications may be made in the adaptation of the device to various conditions, without departing from the spirit and scope of my invention.

I claim:—

1. A feeding device capable of being used to feed clothes to a wringer, including a feed plate having one edge capable of insertion between the rollers of the wringer, a

handle for said plate, and abutment strips ²⁰ arranged at the ends of said plate with said edge of the plate projecting beyond the forward edges of said strips.

2. A feeding device capable of being used to feed clothes to a wringer, including a ²⁵ feed plate having one edge capable of insertion between the rollers of the wringer, a handle for said plate, and abutment strips formed on said plate and extending transversely and equi-distantly on opposite sides ³⁰ thereof with the forward edge of said plate projecting beyond the adjacent edges of said strips, the lower ends of said strips being capable of engagement with a guide board of the wringer to guide said plate ³⁵ into the space between said rollers.

EDWARD WALKER.
